DESIGN FOR A SHOE

George H. Gillis, Fitchburg, Mass.

Application October 22, 1940, Serial No. 95,991

Term of patent 7 years

To all whom it may concern:

Be it known that I, George H. Gillis, a citizen of the United States, residing at Fitchburg, in the county of Worcester and State of Massachusetts, have invented a new, original, and ornamental Design for a Shoe, of which the following is a specification, reference being had to the accompanying drawing, forming part thereof.

my new design, the opposite side presenting substantially the same appearance as the side shown.

I claim:

The ornamental design for a shoe, as shown and described.

GEORGE H. GILLIS.
